CLAIM

The ornamental design for a space heater, as shown and described.

DESCRIPTION

FIG. 1 is a front perspective view of a space heater showing my new design;
FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an enlarged view of portion 9 shown in FIG. 1; and,
FIG. 10 is an enlarged view of portion 10 shown in FIG. 2.
The dash-dash broken lines in the drawings depict portions of the space heater that form no part of the claimed design.
The dot-dash broken lines denote the boundaries of the detail views and form no part of the claimed design.
In FIGS. 1-4 and 9-10, the features visible behind the front and rear grates form no part of the claimed design.

1 Claim, 10 Drawing Sheets
